[57] CLAIM

The ornamental design for a cauterization smoke evacuator, as shown and described.

DESCRIPTION

FIG. 1 is a perspective view of the cauterization smoke evacuator showing our new design;

FIG. 2 is a top plan view thereof;

FIG. 3 is a top plan view;

FIG. 4 is a right side elevational view thereof, the left side elevational view being a mirror image thereto;

FIG. 5 is a bottom plan view thereof;

FIG. 6 is a front elevational view thereof; and,

FIG. 7 is a rear elevational view thereof.

The broken line showing in FIGS. 1 and 2 is for illustrative purposes only and forms no part of the claimed design.
